UNITED STATES PATENT OFFICE.

EMILE JOSEPH PEGLER, OF NEW YORK, N. Y.

WATER-CIRCULATING RADIATOR.

1,181,404.

Specification of Letters Patent.

Patented May 2, 1916.

Application filed April 30, 1915. Serial No. 24,937.

To all whom it may concern:

Be it known that I, EMILE JOSEPH PEGLER, a citizen of the United States of America, and a resident of the borough of Manhattan, 5 in the city, county, and State of New York, have invented certain new and useful Improvements in Water-Circulating Radiators, of which the following is a specification, reference being had to the accompanying drawings.

This invention relates to improvements in radiators and particularly to improvements in hot-water radiators; and an object of this invention is to provide a hot-water radiator 15 which will contain within itself its own water-heating means and will therefore dispense with the necessity of the installation and maintenance of a boiler plant and of expensive pipe connections therefrom to the 20 radiator and from the latter to radiators in other rooms of the building.

Another object of this invention is to provide a radiator which will in its operation be free from steam pressure and which 25 can be manufactured of comparatively thin metal and therefore economically, and which will radiate a larger proportion of the heat supplied than would a radiator made of heavy material.

30 A third object of this invention is to provide a hot-water radiator which will furnish heat for the same fuel consumption as is now required by large heating plants and which will require no larger heat-radiating 35 surface than is needed by an ordinary steam-radiator.

A further object of this invention is to provide a radiator which will serve to increase the heating value of any fuel.

40 A fifth object of this invention is to provide a radiator which will make it possible to retain the generated heat in the room, the air, vitiated by the burning of oil or gas, being led entirely into the open air, whereby 45 there is attained a sanitary advantage which has been sought for but never obtained before. By means of the radiator hereinafter described, there is solved the problem of saving the cost of expensive steam-heating 50 plants and, at the same time, there are moreover provided radiators which give equal comfort and are more sanitary in their operation and are within the reach of the purse of the rich and poor alike. The essential 55 feature which lies at the basis of the radiator forming the subject of this invention is

the great velocity with which the water circulates in the radiator despite the small amount of fuel consumed.

This invention consists of the construction, arrangement and combination of parts designed to produce a radiator made up principally of tubular annular or ring-like metal sections that are heated by means and in a manner designed to prevent the vitiation of the air and to secure at the same time a rapid circulation of the water in all parts of the radiator section.

The way in which the foregoing objects are attained in the most practical and simple manner is described hereinafter with reference to the accompanying drawings, in which similar characters denote corresponding parts throughout the several views and in which—

Figure 1 represents in front elevation a hot-water radiator consisting of several annular or ring-like sections in each of which the water circulates independently; Fig. 1^a is a side view of what is shown in Fig. 1; Fig. 1^b is a detail showing the face of a ventilator; Fig. 1^c is a detail which shows an individual or independent heating chamber and the tubular parts of the section connected therewith; Fig. 2 shows in perspective a modified form of this invention in which the radiator consists of a single ring-like section; Fig. 3 illustrates a radiator consisting of a series of ringlike sections, the end of the last section being connected with the beginning of the first section; Figs. 3^a and 3^b are, respectively, a side and a top view of the radiator illustrated in Fig. 3; Fig. 4 illustrates in elevation a modified form of this invention in which the radiator consists of a number of ringlike sections assembled around a common centrally-disposed burner casing from which each of the sections is heated; and Fig. 4^a is a horizontal section of the radiator illustrated in Fig. 4, the section being taken on the line 5—5 of Fig. 4. Fig. 5 is a partial elevation, divided on (center) line 1—1, and a partial cross-section taken on line 3—3 of Fig. 5^a, showing a radiator of ring like sections assembled around a centrally located burner casing, and a round water-container, enveloping a burner. Fig. 5^a is the half horizontal section of the radiator illustrated in Fig. 5, being taken on line 2—2 of Fig. 5.

In Fig. 1 there is illustrated in front elevation a hot-water radiator which comprises

a series of spaced ring-like, annular or O-shaped metal tubes, which may have a circular, elliptical, square or other suitable cross-section. Each of these sections includes two vertical legs O, O², connected at their upper ends by a substantially semi-circular curved portion O¹. At the lower end of the leg O² there is formed a semi-circular-prolongation or extension O³ having substantially the same curvature as the upper curved part O¹. These ring-like sections are arranged in a row and are spaced apart and give to the radiator its width. Near the bottom of the radiator, there is arranged a horizontally-disposed shallow water-container N, which runs widthwise from end to end throughout the whole width of the radiator. The inner side of the column O communicates with one side of the water-container N; the connected portions of both being cut away. Extending horizontally within the water-container there is a burner-casing A which is surrounded by the water held in the water-container N. Into one end of this casing A there projects a fuel-pipe B and the inner end of the latter is in the form of a burner B¹. From the other end of the casing A there leads an exhaust-pipe C which is designed to carry off the waste products of combustion. The burner B¹ may be suitable for the burning of liquid or gaseous fuel, for example. In one of its side faces (not visible in Fig. 1), the shell of the water-container N is formed with an opening that is closed by a small door F (Fig. 1^b) in which there is arranged a ventilator V in the form of a small exhaust-fan of the approved type commonly used in the windows of stores, shops and the like. The door F closes a watertight air-passage P which leads from the ventilator V to the interior of the casing A surrounding the burner-chamber; and, through this passage P, there flows the air which supports the combustion within the burner-chamber. The small exhaust-fan V prevents the air from flowing backwardly through the passage P. The heated water flows upwardly from the water-container N into the legs O of the several sections and changes its direction of flow in passing through the curved portion O¹ and thereafter flows by gravity downwardly through the other leg O² and enters the water-container again through the curved lower portion O³. Above the sections and extending widthwise thereof, there is mounted a metal box H which is designed to receive the water which, by reason of the expansion thereof, enters the metal box H through the small pipes K. In the top of the metal box H, there is provided a door J, through the opening closed by which there may be poured water, when it is desired to replenish the supply of water in the radiator sec-

tions. Of course, the door J is normally kept closed.

In Fig. 1^c there is illustrated in detail the lower part of a radiator section, the tubular legs of which are elliptical in cross-section and communicate with the water-container N¹. In this case, there is an individual or separate water-container N¹ for each section. The burner-casing A and burner B¹ extend horizontally through the several water-containers N¹. By this provision of a separate or individual water-container for each section, it results that there is no superfluous quantity of water heated.

The radiator shown in Fig. 2 is made up of a single ring-like or annular section consisting of an outer shell O, O¹, O², O³, and an inner shell I separated from the outer shell by an interval of about two inches.

The inner and outer shells are connected and the space between them is closed by the end walls E.

In the top of the outer shell there are formed two openings K, K¹, which are normally closed by screw-caps.

The water space may be filled by water poured through one of the openings, the other hole then serving to permit the escape of air.

Near the bottom of the leg O of the water space, there is arranged a horizontally-extending burner-casing A, into one end of which there ex-

100 tends a fuel-pipe B and from the other end of which there leads an exhaust-pipe C to carry away the waste products of combustion.

At N², opposite the burner-casing A, the inner shell I projects inwardly so as to afford sufficient space for the circulation of

the water around the casing A. The fuel-pipe B terminates within the burner-casing A in a suitable burner.

That end of the burner-casing A which is opposite from the exhaust pipe C projects from the end wall E, to be covered with round cap F³ used as

105 a door for lighting. Fuel supply pipe B goes through the center of the cap F³ as an axis.

The cover or top of said cap F³ is a small revolving fan V, of any approved type as described in connection with Fig. 1.

On the drawing of Fig. 2 this cap is shown removed for better illustration.

The heated water rises, as before, in the upright portion or water leg O, changes direction at the top O¹, falls by gravity through the other water leg O² and returns through the curved part O³.

An expansion chamber (such as the chamber H of Fig. 1) may be dispensed with by putting a mark H¹ on the radiator to indicate the proper level of the water when the radiator is cold.

A water gage is unnecessary; for, the level of the water can be ascertained by tapping or touching the thin metal shell with the hand.

Fig. 3 illustrates in front elevation a hot-water radiator comprising a series of ring-like sections which are made of drawn metal

tubing and are connected one to the other so that the hot water will travel continuously from one section to another throughout the whole system. Each section has an upright 5 or substantially vertical leg O which is connected at its top by a semi-circular part O¹ to the other leg O⁴ which is inclined slightly and is joined to the vertical leg O of the next succeeding or adjacent section by the 10 curved part O⁵. The top of the last leg O is connected, by a horizontal tubular portion H², with the top of the first inclined leg O⁴, so that the water flows in a closed circuit from one section to the other, as is indicated 15 by the arrows in Figs. 3, 3^a. The horizontal connecting part H² is placed above the sections, instead of below the same, so that this part H² may be provided with a door J through the opening closed by which the 20 supply of water may be replenished; but it would be perfectly feasible to place the connecting part H² below the sections, in which case the water would flow through this part in the opposite direction. The water in the 25 several sections of the radiator is, as could be the case of the other forms of radiator herein described, heated by an electric conductor through the sections B^x of which flows the electric current. There is a section B^x of 30 the electric conductor mounted in the lower part of each of the several substantially vertical water-legs O.

In Fig. 4 there is illustrated a round hot-water radiator comprising a series of ring-like radiator-sections made of stamped or drawn-metal tubing and arranged around a centrally-disposed vertical burner-casing A which is closed, at the level of the upper ends of the legs O, by the circular plate W and 35 into the lower end of which there projects a burner of any suitable type (not shown); and, from the upper end of the burner-casing A, there leads, through an opening in the plate W, an exhaust-pipe C which carries off the waste products of combustion. By this arrangement, the several legs O are exposed to the heat from the common burner-casing A. Above the radiator there is arranged a water-drum H³ which serves as an 40 expansion chamber, this drum being connected by pipes K with each of the several sections. A door J in the drum H³ closes an opening through which the water supply may be replenished. At its center the drum 45 H³ has a watertight passage through which extends the outlet pipe C. The drum H³ is shown round but it may be of any other suitable form; for example, it might be of an octagonal shape similar to that of the skeleton frame or spider X which is supported by the radiator legs Y and which supports the 50 radiator-sections.

The burner-casing A may be left open at its lower end, through which the cold air 55 enters to support the combustion; and the

heated waste products of combustion will rise and flow away through the exhaust pipe C and cannot accumulate in the room to be heated. The water is heated simultaneously in each of the inner legs O of the 70 several sections, changes its direction at the parts O¹, falls by gravity through the outer legs O² and rapidly returns to the legs O through the curved lower parts O³.

Fig. 5 represents a round hot water radiator, similar to that shown in Fig. 4, comprising a series of ringlike radiator sections made of stamped or drawn metal tubing, and assembled around a centrally disposed vertical burner casing A² which is closed at 75 the level of the upper ends of the legs O, by the circular plate W; and in the lower end of which there is a round burner B² located, of any suitable type, with an opening F² at its center as fresh air intake. Said 80 burner is surrounded by the water container N³, which container substitutes the inner half of the bottom curve O³ of each section, these being cut away, like in Fig. 1^c. Said water-container N³ feeds simultaneously the 85 columns O of each section, and receives back the unheated water from O³, similarly as in Figs. 1 and 2. Plate W is connected at its center with exhaust pipe C which carries off the waste products of combustion. For 90 filling the sections with water a round drum can be used, as described and shown in connection with Fig. 4; to receive the said drum there are flanged holes K² at the top of each section. The burner B² may be 100 suitable for the consumption of liquid, gaseous or electric fuel. Letter X indicates the skeleton frame or spider which supports the radiator sections, and has legs marked Y. The water being heated simultaneously 105 in each of the inner legs O of the several sections, changes its direction at the bend O¹, falls by gravity through the outer legs O² and rapidly returns through the curved lower part O³ to the container N³. 110

It is obvious that the combustion of a suitable fuel could be made to take place at a point lower than that shown in Figs. 1, 2 and 3; but the combustion must in any case take place at a point higher than the 115 lowest point of the curved portion O³, in order that the water may be made to rise in one of the legs and flow down the other leg of the section, as hereinbefore explained.

Although the forms of radiator hereinbefore described and shown differ somewhat in appearance and arrangement of parts, yet the mode of operation of all the several forms is the same. In each of these forms, the water-column in the leg on the side on which the water-heating unit is arranged is caused to rise upwardly, while the water-column in the other leg of the section flows by gravity downwardly to take the place of the heated water-column and thereby there 125 130

is produced automatically a constant circulation of the water; and therefore the radiator is called by me a water-circulating radiator.

5 I claim:

1. A self-circulating hot-water radiator of the character described, including a tubular section built up to an endless closed O-shaped upright section having a pair of vertical columns in communication with each other by curved portions of the same sectional area; a closed burner casing enveloped in one of said columns near and above its bottom and surrounded by water, 10
- 15 a revolving fan thereon as air-inlet and an exhaust pipe as air-outlet, arranged to cause circulation of the water by heating one of the columns above the bottom thereof; the water flowing downwardly in the other unheated column to take the place of the upwardly flowing heated water.

2. A self-circulating radiator proper of the character described, including a series of spaced tubular O-shaped upright sections, 25 each section having a pair of vertical columns with curved top and bottom portions of the same sectional area, a heated water-container adapted at one side of the bottom curve as substitution thereof, longitudinally common to all the sections, feeding each section with hot water and receiving the contents of each section, a closed burner-casing within said water-container surrounded by water, a revolving fan there-

on as air-inlet and an exhaust pipe as air-outlet.

3. A self-circulating hot-water radiator of the character described, including a series of tubular O-shaped upright sections, each section having a pair of vertical columns, 40 with curved top and bottom portions of the same sectional area, a heated water-container adapted at one side of the bottom curve as substitution thereof, common to all the sections, feeding each section with hot water and receiving the contents of each section, a burner casing within said water-container surrounded by water, and an exhaust pipe thereon as air-outlet.

4. A self-circulating hot-water radiator 50 of the character described, including a series of tubular O-shaped upright sections, each section having a pair of vertical columns with curved top and bottom portions of the same sectional area, a heated water-container adapted at one side of the bottom curve as substitution thereof, a burner casing heating one column of each section, to cause circulation of the water.

Signed at the borough of Manhattan, city, 60 county, and State of New York, this twenty-ninth day of April, A. D. 1915, in the presence of the two undersigned witnesses.

E. JOSEPH PEGLER.
